UNITED STATES PATENT OFFICE

DAVID S. JACOBUS, OF MONTCLAIR, AND NATHAN E. LEWIS, OF PLAINFIELD, NEW JERSEY, ASSIGNEES, BY MESNE ASSIGNMENTS, TO FULLER LEHIGH COMPANY, A CORPORATION OF DELAWARE

SECTIONAL FURNACE WALL

Application filed October 21, 1925, Serial No. 63,855. Renewed June 25, 1930.

Our invention relates to improvements in furnaces, and particularly the walls thereof, which are adapted to be air cooled, and will be best understood from the following description and the annexed drawings, in which Fig. 1 is a vertical section of a form of furnace chamber for steam boiler, which we have chosen for purposes of illustration of our invention; Fig. 2 is an enlarged horizontal section through one side of the wall; Fig. 3 is a corresponding vertical section; Fig. 4 is a side view of the wall with the casing removed; Fig. 5 is an edge view of one of the tile supporting plates; Figs. 6, 15 and 8 are top, side and perspective views, respectively, of one form of a tile; Figs. 9, 10 and 11 are top, edge and front views, respectively, of a second form of tile or a sectional top tile; Figs. 12, 13 and 14 are 10 top, edge and perspective views, respectively, of a third form of tile or a sectional base tile; Figs. 15 and 16 are sectional and side views, respectively, showing on an enlarged scale the joints of the plates shown 15 in Fig. 4, Fig. 15 being a section along the line 15—15 of Fig. 16, and Figs. 17 and 18 are sectional and side views, respectively, of a modification showing the joints of the plates, Fig. 18 being a section taken along 20 the line 18—18 of Fig. 17, the last four views being partly broken away.

In the drawings, reference character 1 represents a furnace that is provided with a bottom portion 2, in the shape of an inverted hollowed pyramid. The bottom portion 2 may be lined with fire-brick and provided with stretcher courses 2' of tile at intervals, and may have plates 2" on the outside thereof. A fuel burner 3 is shown near 25 the top of the furnace. Boiler tubes 4 are shown installed near the top of the furnace, these tubes being mounted in headers 5 and 6 in a well-known manner. The boiler setting is mounted on pillars 7, across the 30 top of which I-beams 8 are installed.

Fig. 1 is an illustration of this invention shown adapted to an air cooled furnace. For this purpose a casing is installed around the outside of the lining 14 or furnace wall 35 proper, with a space intervening between

the casing and the lining or wall, through which air may be passed, preferably from the rear portion of the furnace along the sides in a somewhat countercurrent direction to the hot products of combustion that are on the inside of the furnace. The hot air may then be passed to the burner 3 or fuel inlet, thus providing hot air for combustion purposes and, at the same time, cooling the furnace walls.

Upright supporting members 9 are located on the I-beams 8 and the flanges thereof next to the furnace are connected to channels 10 (Fig. 2). The I-beams 9 are spaced apart and with channels 10 form an outer framework for the furnace. Plates 11 are secured by their marginal flanges to the flanges of the channels 10. A layer of heat-insulating material 12 is applied to the plates 11 on the inside thereof. The lining or wall of the 70 furnace itself is composed of tile 14, 14', 14" which are held in position by means of tile-holding plates 15, shown in Fig. 5, also known as bulb beam plates. These bulb beam plates 15 are so arranged that sections 75 of the tile can be removed without disturbing other portions thereof. The edges of these tile are so shaped as to prevent passage of radiant heat therebetween, even when the tile do not fit perfectly against each other.

A plurality of tile-supporting plates 15 are provided. The vertical edges of adjacent tiles carried by these plates contact with each other to form substantially air-tight joints and the bottom edge of each plate rests 80 against the top edge of a lower plate. The tile supporting plates 15 are provided with inwardly projecting bulbed vertical ribs 16. The plates 15 are also provided on the side opposite the ribs 16 with horizontally disposed fins 17 for the purpose of increasing radiation to the circulating air and to reduce the average temperature of the furnace brickwork and also to add stiffening to the plates 15. The fins aid in guiding the air 85 along horizontal paths. One side edge of each plate is offset, as shown at 18, so as to adapt each plate for overlapping the edge of an adjacent plate, and the top edge of each plate is bent outwardly or offset, as 90 95 100

shown at 19, for a similar purpose. The bent out portion 19 may be provided with a channel or groove 20 (Fig. 5) to accommodate luting material that will seal the joint between the plates against the passage of air or hot products of combustion. A plurality of clips 25 are provided near the vertical straight edge of each plate 15, opposite the offset edge 18, and a plurality of similar clips 26 are provided near the lower edge of the plates. A course of luting material 27 may be provided along the longitudinal joints between rows of plates 15. The plates 15 are, therefore, permitted to expand and contract without causing undue stresses or strains in adjacent plates.

A plurality of straps 29 are installed between the plates 15 and the casing, these straps being connected at one end to the channel irons 10, by means of angle irons 29', and at the other end to the plates 15. For each strap 29 a corresponding angle brace 30 is provided, these two members forming a bracket which will hold a plate in spaced relation from the support. Each brace 30 is secured to the opposite walls or channels 10 and plates 15 by means of angle irons 29' and 31. By so connecting the plates 15 to the channels 10 and I-beams 9, the plates 15 are supported on the structural members 9, the straps 29 being under compression, and the angle braces 30 under tension, as will be obvious from Fig. 3, so that the plates 15 do not bear heavily on each other to cause danger of the same buckling, even when loaded with the tile 14 which they carry.

The three forms of tile which constitute the lining of the furnace are supported on the plates 15 and are so shaped that one section of tile can be removed and replaced without disturbing sections of tile in the adjacent vertical row. The tile illustrated in Figs. 6, 7 and 8 is the intermediate tile and is provided with curved vertical edges 33, which fit each other when a plurality of these tile are assembled in horizontal rows, thus preventing radiant heat from reaching the plates 15. This tile is also provided with vertical slots or grooves 34 along its edges to adapt the same to be threaded or slipped over the enlarged edges of the ribs 16 on the plates 15. The upper and lower ends of the tile are made sloping, as shown at 35, so that individual tiles resting upon a lower one, will tend to drift into snug contact with the side of the tile-supporting plate 15. The top tile is illustrated in Figs. 9, 10 and 11, and is especially adapted for making the last course of tile for each section. The lower end of the tile 14' is made sloping, as indicated at 35', and the surface of the upper end is made curved, as indicated at 33', the side edges of the tile being made with plain surfaces, as shown at 36. This tile is supported on a

horizontal row of the intermediate tile and against the plate 15, as indicated in Fig. 3, so that it can be readily removed when desired.

The tile shown in Figs. 12, 13 and 14 is the base tile and is the same as that shown in Figs. 6, 7 and 8, except that its rear surface is cut away to form a shoulder 40, which shoulder is adapted to rest on the rib 21 of plate 15, thus preventing the tile from drifting too far down, as shown at 14" in Fig. 3. Its lower surface 33' is formed in a curvature to correspond with the upper surface of a tile 14', the space between the tile being filled with a layer of luting material 27. When a sufficient number of tiles have been assembled on a horizontal row of plates 15 to cover the same, the layer of luting 27 is applied and the tile on the next higher row of plates 15 is installed in a similar manner. When it is desired to remove a section of tile, the uppermost tile 14' on the plate 15 can be readily removed as the ribs 16 terminate short of the upper edge of the plates 15, and the tile 14' simply rests against the inner face of the plate 15 and upon the upper sloping edge of a lower tile. After the topmost tile has been removed, those below can be removed by first sliding the same upwardly along the rib 16 and then outwardly after the upper end of the rib has been passed.

The tile supporting plates themselves, which are preferably made of metal, are assembled by bringing their edges together so that the offset portion 18 of one plate overlaps the edge of the adjacent plate, and the clips 25 on the adjacent plate overlap the offset edge 18, and, in a similar manner, the offset upper edges 19 of these plates overlap the edges of plates in a higher row, and the clips 26 on these plates overlap the offset edges 19 to hold the plates in assembled position, so that they can slide on each other to take care of changes, due to expansion and contraction. The plates are connected to the supports 9 by means of the straps 29 and Z-bars 30, as already explained.

Figs. 15, 16, 17 and 18 indicate how the space where four corners of adjacent plates come together can be made substantially air-tight. Four such adjacent plates are designated by reference characters 15', 15², 15³ and 15⁴, respectively. The edges of the plate 15⁴ are not offset at the corner illustrated in Fig. 16. The offset edge 18' of the plate 15' is cut away, as shown by dotted lines, a sufficient distance to accommodate the offset edge 19³ of the plate 15³, the upper end of the offset edge 18² of the plate 15² being bent outwardly and extended into a flat portion 42² which overlaps the corners of the four plates and luting 43 is placed behind this portion 42². Also a strip of luting is inserted in the groove 20³ of the offset por-

tion 19^a of the plates 15^a. In the modification shown in Figs. 17 and 18, the corners are protected against leakage in a similar manner, except that a separate plate 44 is held on by the screw 45, with luting 46 placed behind the same.

By forming an outer casing for the boiler by means of the plates 11 and channels 10, and applying a layer of insulating material thereto, as above described, and also by forming the plates 15 with overlapping edges and luting material along the edges and at the corners, ducts or channels are formed so as to be substantially air-tight through which air can be passed for cooling the walls without danger of excessive leakage of the air into the furnace, even when under high pressure, as is often the case when air ducts are formed in brick settings for furnaces. While we have shown our invention as applied specifically to the vertical side walls in the embodiment shown, it is nevertheless to be understood that it is equally applicable to any other wall of a furnace and by the term "wall" in the claims, we intend to cover not only the vertically disposed walls, but also the walls which are generally described as floors and roofs of furnaces and by the term "lining", we denote the inner surfaces of those walls, as defined above.

We claim:

1. In a furnace wall, a plurality of supporting members, a casing supported by said members, a plurality of plates spaced from said members and casing, means independently supporting each plate from said members, and means on each plate to hold tile thereon.

2. In a furnace wall, a support having a plurality of brackets thereon, a plurality of plates secured to said brackets and held thereby in spaced relation from said support, each plate being supported by said brackets independently of the other plates, and means on each plate to hold tile thereon.

3. In a furnace wall, a support having a plurality of brackets thereon, a plurality of plates secured to said brackets and held thereby in spaced relation from said support, each plate being supported by said brackets independently of the other plates, and means on each plate to hold tile thereon, said brackets being arranged to permit passage of air horizontally through said space, and horizontally disposed fins on said plates.

4. In a furnace wall, a support, a plurality of plates spaced inwardly from said support, a plurality of brackets secured to said support and extending across said space, means securing each plate directly to at least one of said brackets, and tile supported on said plates.

5. In a furnace wall, a support, a bracket comprising two members secured to the sup-

port at spaced points and extending inwardly from the support, the inner ends of said members being secured together, a plate secured to the inner ends of said members, and tile supported on said plate.

6. In a furnace wall, a support, a bracket comprising two members each having one end secured to the support and extending inwardly therefrom, one of said members being disposed substantially normal to said support and the other inclined thereto, the inner ends of the members being secured together to complete the bracket, a plate secured to the inner end of said bracket, and tile supported on said plate.
